UNITED STATES PATENT OFFICE.

WILLIAM C. KORZINEK, OF WEEHAWKEN HEIGHTS, NEW JERSEY, ASSIGNOR TO
PACIFIC MILLS, OF BOSTON, MASSACHUSETTS, A CORPORATION OF MASSACHUSETTS.

DESIGN FOR TEXTILE FABRIC OR WALL-PAPER.

41,882.

Specification for Design.

Patented Oct. 31, 1911.

Application filed July 18, 1911. Serial No. 639,247. Term of patent 3½ years.

To all whom it may concern:

Be it known that I, WILLIAM C. KORZINEK, a subject of the German Emperor, residing at No. 474 Gregory avenue, Weehawken Heights, in the county of Hudson and State of New Jersey, have invented a new, original, and ornamental Design for Textile Fabrics or Wall-Papers, of which the following is a specification, reference being had to the accompanying drawing, forming part thereof.

The drawing is a plan view of a portion of a textile fabric or wall paper showing my design.

I claim:

The ornamental design for a textile fabric or wall paper, as shown.

WILLIAM C. KORZINEK.
